UNITED STATES PATENT OFFICE

LEON H. BAXTER, OF HUDSON, OHIO

DESIGN FOR A TOY SHIP

Application filed May 24, 1930. Serial No. 35,760. Term of patent 7 years.

To all whom it may concern:

Be it known that I, LEON H. BAXTER, a citizen of the United States, residing at Hudson, in the county of Summit and State of Ohio, have invented a new, original, and ornamental Design for a Toy Ship, of which the following is a specification, reference being had to the accompanying drawing, forming a part thereof.

In the drawing:

The figure is a perspective view of a toy ship with the rear wheel appearing in fragmentary form, showing my new design.

I claim:

The ornamental design for a toy ship as shown.

LEON H. BAXTER.
